CLAIM

The ornamental design for a wearable injector component, as shown and described.

DESCRIPTION

FIG. 1 is a perspective view of a medical instrument showing the new design;

FIG. 2 is a top view thereof;

FIG. 3 is a bottom view thereof;

FIG. 4 is a front view thereof;

FIG. 5 is a back view thereof;

FIG. 6 is a left view thereof; and,

FIG. 7 is a right view thereof.

The broken lines shown in the drawing views are included for the purpose of showing portions of the product that form no part of the claimed design.
